(57) **CLAIM**

The ornamental design for an off-road vehicle side body panel set, as shown and described.

DESCRIPTION

FIG. 1 is a right side elevation view of an off-road vehicle side body panel set showing our new design;

FIG. 2 is a left side elevation view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a front and right side perspective view thereof; and,

FIG. 8 is a rear and left side perspective view thereof.

The broken lines in the drawings illustrate environmental structure of an off-road vehicle and portions of the vehicle's body side panels that form no part of the claimed design.
